SURFACE CONDENSER

Abbott L. Penniman, Baltimore, Md.

Application April 10, 1933, Serial No. 665,413

4 Claims. (CL 257—43)

The present invention relates to steam condensers, and more particularly to steam condensers of the surface type. This application is a continuation in part of applicant's prior application, Serial No. 279,720, filed May 22, 1928, entitled "Surface condensers."

The changes in temperature taking place in a condenser during operation necessitate flexibility of the structure due to the presence of relatively long parts of such condenser structure, which parts consist of different metals and possess different coefficients of expansion. There is considerable range of variation under operating conditions which consequently necessitate flexibility of structure in order to compensate for those variations. Some of the conditions which give rise to the necessity for flexibility of structure are discussed immediately below.

Thus during starting up periods, the air pumps are not able to take care of the air leakage at the shaft glands of modern turbine installations. A similar condition exists when the air pump fails to function properly, during the operation of the condenser. In either case, the steam temperature in the condenser and, accordingly the temperature of the shell, rises considerably and may approach or even exceed 212° F. while the tubes retain a temperature close to that of the circulating cooling medium. The result is a lengthening of the shell, as compared with the tube bundle, or a relative shortening of the tube bundle.

Failure of the pumps which circulate the cooling medium through the tubes will cause a rapid rise of the temperature of all parts of the condenser, including tubes and shell. Since the tubes are usually made of non-ferrous metal and have a larger coefficient of expansion than the ferrous shell, the result of this condition is a relative lengthening of the tube bundle, as compared with the shell.

The features described immediately above will illustrate the necessity for flexibility of structure in these surface type condensers, particularly steam condensers. In practical application, two types to secure flexibility of structure have been generally employed. One expedient employed in the prior art is the use of packing, and the tubes of surface condensers have been secured to the tube sheets in a manner as by packing at one or both ends, to permit expansion and contraction with change of temperature. When either or both ends of the tube are placed so as to be free to expand, it is necessary to stay the tube sheets sufficiently to prevent their col-

lapse due to the relatively large stresses set up in the tube sheets on account of the difference in pressure on the two sides of the sheets. This method of securing the tubes has caused considerable trouble not only in the operation of the condenser, but also in the operation of the associated power plant elements.

One serious disadvantage of packing the tubes arises because, in many instances, the packing, after a comparatively short period of condenser operation, becomes compacted to such a degree as to prevent the movement of the tubes. Thus the packing loses its function and the condenser cannot be safely operated until the packing is renewed. The renewal of the packing means a shut-down in the operation of the condenser and the associated engine or turbine and power plant accessories. Moreover, it is difficult to ascertain the condition of the packing and, unless the packing is renewed with a frequency providing for a great factor of safety, the useless or harmful condition of the packing may not be ascertained until after serious trouble has occurred.

Another difficulty with packing lies in the fact that there is leakage of circulating water into the condenser, even when the packing is in excellent condition. As is well known to those concerned with the design or operation of condensers, leakage has a serious effect upon the operation of steam boilers because the presence of even a small amount of dissolved or suspended material causes priming and foaming and solids are carried over into the superheater and turbines, clogging the superheater tubes and eroding the turbine blades.

These difficulties which arise in connection with the use of the packing of tubes have led to attempts at solution of the problem by expanding, or otherwise rigidly securing the tubes at both ends of the tube sheets. In one such method, the needed flexibility is obtained by the use of so-called floating tube sheets. One application of this method attempts to compensate for expansion by floating the tube sheet at one end of the condenser upon a rubber expansion joint. This construction has not proved particularly satisfactory, because some tubes, being colder than others, hold the floating tube sheets from movement sufficiently great to follow the expansion of the warmer tubes. The result is a loosening of the tube sheets, resulting in leakage of the circulating water, and the consequent contamination of the condensate. However, the rubber expansion joint is a further source of trouble; for this joint soon loses its leak-proof qualities.

The present invention has for its object means of securing flexibility of structure to compensate for variations due to temperature changes without the utilization of packing and/or floating tube sheets. The flexibility is secured by deflection of the tubes in a predetermined manner as set forth hereafter, with or without deflection of the tube sheets.

The objects and advantages will appear from the detailed description set forth below, it being understood, however, that this detailed description is given by way of illustration only, and not by way of limitation, since various changes therein may be made by those skilled in the art without departing from the scope and spirit of the present invention.

In connection with that more detailed description, there is shown in the drawings, in

Figure 1, a longitudinal section of a two-pass condenser having the present invention embodied therein, in

Figure 2, a fragmentary sectional view on an enlarged scale of a single tube expanded at both ends in the tube sheets and passing through intermediate tube supporting sheets; in

Figure 3, a fragmentary view illustrating the deflection of the tube secured in accordance with the present invention; in

Figure 4, a fragmentary sectional view on an enlarged scale of one of the tube sheets as mounted on the shell; in

Figure 5, a modified form of structure of tube sheet as mounted on the shell; in

Figure 6, a fragmentary view in cross section of the condenser; and in

Figure 7, a fragmentary detail view of a baffle and slip joint therefor.

In accordance with the present invention, the condenser is constructed with the tubes expanded at both ends in the tube sheets, or otherwise rigidly secured to said tube sheets. Both tube packing and floating tube sheets are eliminated. Compensation for variations due to temperature changes are effected in the present construction by deflection of the tube bundles with or without deflection of the tube sheets. This construction eliminates the major cause of leakage of circulating water into the condenser. Installation of tubes is simplified. And as there is no packing to dry out or any diaphragm expansion joint to be affected, the condenser may be permitted to dry out during shut-down periods, and can be baked to remove scale. Other advantages will also be apparent to those skilled in the art from the further description set forth below.

The present invention is concerned with condensers having condenser tubes of a length which require some means for compensating for the variations that take place with change of temperature. In order to obtain the desired flexibility it is necessary to have tubes which behave as "long slender columns". For purposes of the present invention, such tubes are defined to have a length resulting in a ratio of slenderness of 200 or more. The "ratio of slenderness" is equal to the length divided by the radius of gyration. This invention enables the use of tube condensers having relatively long tubes as described above, and makes possible the practical use of such tubes, both ends of which are expanded into the tube sheets. In accordance with the present invention, the slenderness of the long tubes causes the relative lengthening of the tube bundle, as compared with the shell, to be compensated mainly by deflection of the tubes,

and only to a small extent by deflection of the relatively stiffer tube sheets. It is necessary to guide the deflection of the tubes in such a way that the location of the tubes relative to each other, as it has been designed for best steam flow and best condensing conditions, is not changed, and that the longitudinal thrust in the tubes which stresses the metal of the tubes and tends to loosen the expanded joints of the tubes in the sheets, be kept as small as possible. The following analysis of the conditions to be considered in this respect shows and indicates the progress in the art which is obtained by the use of the present invention.

For satisfactory operation, it is necessary that the support plates, during deflection, serve mainly as guides for the tubes only, and that they do not take up any appreciable bearing pressures resulting from the deflection. Such pressures decrease the service life of the tubes, on account of wear caused by friction and vibration, and, in addition, void the mathematical determination of the shape of the tubes to be taken on expansion because the combination of pressure and friction causes the tube sections located in the support plate holes to act in a way similar to fixed points, more or less, and, therefore, eliminates free deflection. In addition, the introduction of such fixed points either increases the thrust to be taken up by the fixed ends of the tubes or makes it necessary to provide for movement of the ends by deflection of the sheets.

Several methods are provided by the present invention for obtaining the conditions outlined above. One is to avoid the use of any means of support in the center or near to it as would be obtained with the utilization of one support plate only or any other uneven number of supports. The use of one support plate in the center of the condenser results in causing a fixed point in the center of the tube, on expansion, with either half of the tube free to deflect in any direction. The deflection, therefore, is not under control. The use of three support plates, with one support in the center, limits the movement of the center section of the tubes, on expansion. This condition results not only in excessive tube wear at the center support plate, but also in a corresponding increase of the end thrust since it cuts the effective columnar length in half. In addition, the pressure forces the deflection between support plates into directions which cannot always be calculated. This identical condition appears with the use of any uneven number of support plates.

The proper guidance of deflection on expansion necessitates the presence of certain curvatures of the tubes on installation. Any expansion with the ends fixed tends to increase the curvature of all sections which are already curved. Accordingly, if the support plate holes are intended to serve as guides only, the tubes must be substantially straight in the sections passing through the holes. Since more or less all of a slender tube takes a part in the deflection on expansion, the condition can be obtained only by changing directions of curvings and locating the reversing points at the support plates. The use of a single bow throughout the tube eliminates straight sections and reversals and the expansion causes wear and kinking of the tubes at the support plates. In the present invention, reversal of curvings is utilized and is obtained by off-setting the holes in the support plates from the axis of the holes in the tube sheets and by suitable arrangement of the holes in the support plates.

The most favorable and least expensive method is to drill the holes in a vertical tube sheet perpendicular to the sheet, and to locate the component holes in the support plates somewhat higher. The 5 result is an initial downward bend in the end sections, or a stress condition tending to effect such a bending, and an upward bend in the center section, with reversing points at the tube support plates and with perfect drainage of the tubes when 10 the condenser is emptied since no part of the tube, excepting when it is hot, is lower than the ends. The elevation of the holes in the support plates, above the holes in the tube sheets, may be chosen 15 only large enough to insure good drainage of the tubes or slightly larger though it should be considered that increasing elevation increases the flexibility of the structure. The holes in the support plates must be tapered, with the diameter increasing from the center to the outside, to allow 20 good bearing support for the tubes at any angle they may assume during deflection. These angles can be determined either by experiment or by calculation and depend on various factors, as length of intermediate sections and elevation 25 of the holes in the support plates above the axis of the component holes in the tube sheets.

Since the supports are to serve as guides and since this condition demands the use of compound curves with points of reversal at the supports, further limitations appear in regard to the arrangement of the support plates. The most favorable conditions are obtained with two supports especially when the center section is made longer than the end sections, preferably the distance 30 between the tube sheets and the support plates giving tube sections having a length corresponding to a ratio of slenderness of not less than 65. The use of two supports is satisfactory with all tube lengths employed so far. With 40 four supports, bearing pressures at the supports cannot be eliminated, but can be kept down by making the center section and the end sections long and the two remaining sections as short as possible. In such constructions using four supports, desirably the center sections of the tubes between the tube supports are made longer than the end sections of the tubes, and the end sections of the tubes have a length corresponding to a ratio of slenderness of not less than 65. The remaining 45 tube sections should be kept as short as possible. The tubes will be essentially straight in these two sections, with pronounced bending effects at the supports unless the openings through which the tubes pass in these supports are sufficiently large especially in the direction of bending of the tubes. With six supports, the center section should again be longer than either one of the other sections; each of these sections should be a length enabling it to participate in the deflection without causing high end thrusts. With 50 any number of support plates, all sections intended for appreciable deflection should behave at least as medium length columns to facilitate deflection and to lower compressive forces. For 55 practical reasons, any such section should have a length corresponding to a ratio of slenderness of not less than 65.

Unless all tubes are subjected to prebowing, the relative shortening of the tube bundle can be 60 taken care of by a straightening of the tubes, to a small extent only. The present invention relates to various means of making the tube sheet sufficiently flexible to deflect to the extent needed. The desirability of using flexible tube sheets in 65 combination with long tubes has not been previ-

ously recognized in the prior art. Flexibility is obtained by the use of unstayed sheets only sufficiently thick to secure satisfactory expansion of the tube ends, and is increased by providing a space between the periphery of the tube bundles and the rigidly fixed surface of the sheets, such space being sufficiently large to allow for deflection of the tube sheets within the limits of elastic deformation of the metal. This condition may be aided by thinning the tube sheet outside of the 10 tube bundle. The space can be obtained either by spacing the periphery of the tube bundle a corresponding amount from the shell, in which case baffles must be employed to force all of the steam to enter the space within the tube bundle, 15 or by providing a special off-set flange section, as shown for example in Figure 4 and Figure 5.

Turning to a consideration of the condenser structure illustrated in the drawings, exemplifying the invention discussed above, the condenser 20 comprises a shell 10 having a steam inlet 11 and a condensate outlet 12. A circulating water inlet-outlet header 13 is bolted to the shell 10 at one end thereof, and a water reversing header 14 is bolted to the shell at the other end. Tube 25 sheets 15 and 16 are rigidly secured between the ends of the shell 10 and the headers 13 and 14, respectively. Tubes 17 are expanded at both ends in the tube sheets 15 and 16 and extend through support plates 18 and 19 suitably secured to the 30 condenser shell. A baffle plate 20 causes a more even distribution of the steam within the shell and is illustrative of many devices including tube arrangements providing steam lanes, for effecting a good steam distribution within the condenser. 35

As shown in Figure 2, the tube supporting plates 18 and 19 have holes 21 and 22 respectively for the passage of each tube 17 therethrough. These holes in the supporting plates are out of line in a vertical plane with the corresponding holes 23 40 and 24 in the tube sheets 15 and 16, in which the respective tubes are rolled or expanded. In a condenser fitted with 1 inch outer diameter Admiralty tubes eighteen feet long, the holes 21 and 22 desirably should be not less than one inch higher than the corresponding tube sheet holes 23 and 24, and there should be a tube clearance in the holes 21 and 22 of about $\frac{1}{8}$ " gradually increasing to a clearance of $\frac{3}{16}$ " at the outside, with rounded edges. Preferably, the surface is an arc 45 of a large circle so that kinking of the tube is eliminated. The tube expanding with increase in temperature deflects in a compound curve as described above, the relative position and/or direction of the holes in the tube sheets and tube supporting sheets tending to guide the direction of deflection. The present invention is concerned with the use of two or other even number of support plates, two being used as illustrative in the drawings, since it is the usual practice to use two plates with condenser tube lengths of from 12 to 50 26 feet, and this represents by far the bulk of condensers in service at the present time. It is also obvious that the greater the misalignment of the holes in the support plates with respect to the tube plates, the greater the tendency for the tubes to deflect. There is, however, a definite disadvantage in having the tube support plates misaligned to too great an extent in that it makes the problem of renewing tubes particularly difficult. It, therefore, becomes necessary to determine a distance which the holes in the tube support plates should be offset that will provide satisfactory operation of the condenser without an 55 unreasonable amount of difficulty in replacing the 70 tubes. 75

tubes. By experimentation, it has been determined that in a condenser using tubes varying in length from 16 to 26 feet, if the vertical misalignment of the tube holes in the tube support plates with respect to the tube sheets was 1 inch, the condenser performed satisfactorily, and that it was not unreasonably troublesome to replace the tubes.

Instead of calculating the most desirable location of the support plates and of the relative location of the holes, for the best combination of low thrust at the tube ends and easy replacement of tubes, a full scale experimental apparatus may be set up.

Figure 3 illustrates an experimental apparatus which was set up, and shows the behavior of tubes installed according to the present invention, and illustrates a record obtained photographically of such experimental installation as a result of double exposure. The tube, in this case, was 18 feet long. With an elevation of the holes in the intermediate support plates of one inch above the holes in the supports representing the sheets, the cold tube A showed a very slight curvature only. The increase of curvature, as caused by expansion on account of heating, shows plainly the compound nature of the curvature which is a fundamental characteristic of structures produced in accordance with the present invention. Thus the hot tube is shown in position B in Figure 3, and definitely shows the compound curvature resulting by controlling the character of deflection of the tubes in accordance with the present invention in order to compensate for variations due to temperature changes.

As pointed out above, the flexibility of the condenser structure may be increased by flexibility of the tube sheets especially when the initial curvature of the tubes is small. When the tubes are stressed in tension on account of the shell becoming hotter than the tubes, the stresses have to be taken up first by straightening of the tubes as far as possible, second by deformation of tubes and/or tube sheets. It is obvious that if a tube is attached to the tube sheets directly adjacent to the point of support of the tube sheet at its perimeter, all of the stress set up in the tube resolves itself as tension in the tube and shear in the tube sheet. Since the possible non-destructive shear deformation is small, and the force required to cause such shear deformation is large, the stresses will result in elastic stretching of the tube metal followed by loosening of the ends in the sheets or by permanent stretching of the tubes if the stresses are not sufficiently relieved by the elastic deformation.

The present invention provides a distance between the periphery of the tube bundle and the perimeter of the tube sheet at the point of attachment to the shell. This distance is to be calculated in such a way that the stresses resulting from the relative expansion of the shell can be taken up by a combination of elastic stretching of the tubes and elastic bending of the tube sheet, including the space located between the periphery of the tube bundle and the point of attachment, in such a way that the stress within the tube remains below that necessary for loosening the joints in the tube sheets or exceeding the elastic limit of the tube metal.

The necessary distance between tube bundle and point of attachment of the tube sheet to the shell may be procured by spacing the tube bundle a corresponding distance from the shell in which case it is necessary to provide baffles to

keep the steam from by-passing the tubes. A better method is shown by Figure 4. The tube 17, expanded at 24 in the tube sheet 16 represents the outside tube of the tube bundle. An off-set design of the flange connections of shell and header securing the tube sheet provides the space required for deflection of the sheet. For this purpose the flange 40 of the shell and flange 41 of the header are extended sufficiently to provide off-set portions or shoulders 38 and 39 respectively.

A further means of securing flexibility of the tube sheets is shown in Figure 5. In this case, the tubes 17 are expanded as shown at 24 in the tube sheet 16', the latter having an outermost portion F of reduced thickness. This thinner section of the tube sheet 16' lying between the tube bank and the shell, assists in the deflection which may take place in the tube sheet and provides a greater flexibility therein. Both the construction of Figure 4 and Figure 5 may be utilized simultaneously, a method whose advantage is indicated by a comparison of Figure 4 and Figure 5; however, one or the other is usually sufficient to provide for the necessary flexibility of the tube sheet.

For example, the free distance of the tube sheet between the periphery of the tube bundle and the side of the shell in the condensers built in accordance with this invention was approximately 4 inches in condensers which were equipped with approximately 7350 $\frac{1}{2}$ inch outer diameter tubes, the tube sheets being 12 feet in diameter at the point of attachment to the shell.

The use of individual plates or tube supports, as outlined above, is the simplest and cheapest means of taking care of supporting and guiding the tubes. However, the present invention is not limited to such means, but covers any means of support which obtain the desired end, that is to force a compound curving of the tubes with reversals or straight sections at or near the points of support.

Baffles may be required for various purposes within the condenser and are attached to the shell, the tube supporting sheets, and the tube sheets. Means devised to obtain flexibility of structure by deflection of the sheets include methods to permit flexibility in the fastening of these baffle plates as described immediately below.

The general path of the steam is across the tubes in substantially a vertically downward direction. The saturated noncondensable gases which tend to collect in the bottom of the condenser are drawn across a part of the tube bank designated generally by the reference character 26 as shown more clearly in Figure 6. This section of the tube bank is separated from the rest of the tubes by a rain plate 27 which may be in sections 27a, 27b, and 27c extending longitudinally of the condenser shell, and which are supported between the tube sheets and tube supporting plates, as may be necessary, as shown more clearly in Figure 1. In order that the tube sheets may deflect, it is necessary that those sections of the rain plate 27 located between the tube sheets 15 and 16 and the adjacent supporting plates be attached to either the tube sheet or the adjacent supporting plate by means permitting the rain plate sections to slip with respect to the tube sheet or tube supporting plate. As here shown, the rain plate section 27a has one end thereof rigidly secured to the tube supporting plate 19

while the other end thereof is secured to the tube sheet 16 by the clamping plates 28 and 29 which form a slip joint. The rain plate section 27b may be rigidly secured at both ends to the 5 tube supporting plates 18 and 19.

The rain plate section 27c may have one end rigidly secured to the tube supporting plate 18, and while its other end is secured to the tube sheet 15 by means of the slip joint comprising 10 clamping plates 30 and 31. The construction of the slip joint is shown more clearly in Figure 7. The rain plate section 27a, for example, is clamped between the plates 28 and 29 which are rigidly secured to the tube sheet 16 by means of 15 the bolts 32. The rain plate is attached tightly to the wall of the condenser in any suitable manner, as by the rivets 27', as shown more clearly in Figure 6. The tight joints are necessary by reason of the fact that unless the non-condensable vapor which is super-saturated with condensable vapor is forced to travel over a sufficient section of cold tubes to condense out practically all of the condensable vapor, the air pump will not have sufficient capacity to handle 20 the mixture of condensable and non-condensable vapors that would be delivered to it.

As outlined above, another type of baffle is desirably used whenever flexibility of the tube sheets is secured by means involving the spacing 30 of the periphery of the tube bundle at a distance from the shell. Thus in order to eliminate excessive by-passing of the steam around the tube bundle, baffles as represented by plate 34 may be used.

35 In the prior art standard surface condenser with packed tube ends, baffle plate 34, of course, is not used; however, rain plate 27, or some substitute for it, must be used and it has been a well known fact that one of the most prolific causes of 40 poor condenser performance has been due to leakage past rain plate 27, thereby allowing the air pump to become overloaded. Therefore, the baffle plates are supported in sections between the tube sheets and tube support plates, and must be fastened against the tube sheets, tube support plates, 45 and the condenser shell in such a manner as to be substantially vapor tight, despite the fact that the two tube sheets must be able to breathe each toward one another or away from one another, 50 depending upon the stresses set up by the relative temperatures of the several parts of the condenser. It is, therefore, obviously desirable to fit both of these baffles with some form of slip joint at the point where they are attached to the tube 55 sheets.

It will be understood that condensers employing the present invention may be generally of any well known type, the construction being modified to permit of the embodiment presented by the 60 present invention. The tube sheets may be rigidly secured in any suitable manner as alternative to the construction illustrated. Instead of

expanding the tubes in the tube sheets they may be similarly associated therewith by any suitable arrangement preventing relative movement therebetween and assuring a leak-proof joint. As indicated above, an even number of tube supporting sheets must be used, but the exact number will depend on the design of the condenser. Other changes in the construction and arrangement of parts may be made without departing from the invention.

Further, it should be noted, that while certain theoretical considerations have been included in the more specific description of the invention as set forth above, this disclosure should not be interpreted as limited by those theories of operation, 10 since those considerations have been given merely by way of explanation and not as limitations on the structure herein disclosed.

Having thus set forth my invention, I claim:

1. A surface condenser comprising a shell, two 20 approximately vertical tube sheets rigidly supported in said shell, two approximately vertical fixed tube supports placed intermediate said tube sheets, tubes expanded at both ends into horizontal holes in said tube sheets, the centers of the 25 holes in said tube supports being located above the axis of the corresponding holes in said tube sheets.

2. A surface condenser comprising a shell, two 30 approximately vertical tube sheets rigidly supported in said shell, two approximately vertical fixed tube supports placed intermediate said tube sheets, tubes expanded at both ends into horizontal holes in said tube sheets, the centers of the 35 holes in said tube supports being located above the axis of the corresponding holes in said tube sheets, said holes in said supports being enlarged from the center section to the outsides to permit angular displacement of the tubes.

3. A surface condenser comprising a shell, tube 40 sheets rigidly supported in said shell or attached thereto, an even number of fixed tube supports placed intermediate said tube sheets, tubes expanded at both ends into holes in said tube sheets, the holes being substantially at right angles to 45 the tube sheets, and the centers of the holes in the tube supports being located outside of the line joining the centers of corresponding holes in the tube sheets.

4. A surface condenser comprising a shell, tube 50 sheets rigidly supported in said shell or attached thereto, an even number of fixed tube supports placed intermediate said tube sheets, tubes expanded at both ends into holes in said tube sheets, the holes being substantially at right angles to 55 the tube sheets, and the centers of the holes in the tube supports being located outside of the line joining the centers of corresponding holes in the tube sheets, the holes in said tube supports being enlarged from the center section to the outsides to 60 permit angular displacement of said tubes.

ABBOTT L. PENNIMAN.
